UNITED STATES PATENT OFFICE

114,976

DESIGN FOR A DOG SWEATER

Marie Laczko, New York, N. Y.

Application September 12, 1938, Serial No. 79,843

Term of patent 14 years

To all whom it may concern:

Be it known that I, Marie Laczko, a citizen of Hungary, residing at New York, in the county of New York and State of New York, have invented a new, original, and ornamental Design for a Dog Sweater, of which the following is a specification, reference being made to the accompanying drawing, forming part thereof.

I claim:

The ornamental design for a dog sweater, as shown and described.

MARIE LACZKO.
